Primary Examiner — Susan E Krakower*Assistant Examiner* — Jerry Shiuan-Hua Hsu(74) *Attorney, Agent, or Firm* — Crowell & Moring LLP(57) **CLAIM**

The ornamental design for an armrest for a working vehicle, as shown and described.

DESCRIPTION

FIG. 1 is a front perspective view of an armrest for a working vehicle according to the design;
FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view;
FIG. 7 is top plan view thereof;
FIG. 8 is a bottom plan view thereof; and,
FIG. 9 is a reference view showing a possible use of the design.

The dashed broken lines illustrate environmental matter that forms no part of the claimed design. The dot-dash broken lines illustrate unclaimed boundaries that form no part of the claimed design.
